UNITED STATES PATENT OFFICE.

MICHELANGELO SANTELLA, OF MARLBORO, MASSACHUSETTS.

ARCH-SUPPORT.

1,255,794.

Specification of Letters Patent.

Patented Feb. 5, 1918.

Application filed March 1, 1917. Serial No. 151,677.

To all whom it may concern:

Be it known that I, MICHELANGELO SANTELLA, a citizen of the United States, residing at Marlboro, in the county of Middlesex and State of Massachusetts, have invented new and useful Improvements in Arch-Supports, of which the following is a specification.

The present invention relates to supports adapted to be used in footwear to support the arches of the feet of persons suffering from flat foot or fallen arches. The object of the invention is to so form or construct the spring of the support that free resilient yielding of different parts of the arch is permitted without withdrawing or weakening the strength of the support which is given to other parts of the instep, and particularly the inside part thereof. This result is secured by forming the forward part of the spring with or as a series of semi-independent tongues, each of which is springy and is adapted to yield resiliently independently of the others.

In the drawings, Figure 1 is a plan view of an arch support embodying my invention.

Fig. 2 is an under plan view of the same.

Fig. 3 is a longitudinal section on line 3—3 of Fig. 1.

Fig. 4 is a cross section on line 4—4 of Fig. 1.

a represents what may be called the body of the support. Such body may be of any desired construction, ordinary or otherwise. I have found it satisfactory to make the same of a piece of sole leather shaped to conform to the bottom of the human foot from the heel to a point near the ball thereof, and skived at its edges to fit smoothly inside of a shoe. *b* is a spring which is attached by rivets *d* or other fastening means to the body *a* near the heel end thereof. It is of such form, both in outline and in transverse and longitudinal curvature as to support the weak or broken arch of a foot in the desired manner. That part which lies under the arch at the inside of the foot is widened and turned up sharply as indicated at *c* in Figs. 2 and 4, this being a common construction in arch supports.

From the forward end of the spring or spring plate *b* are formed deep cuts *f*, *g* which extend well toward the heel end of the plate. Two such cuts are shown here, but I may make the plate with only one,

or with more than two if desired, according to circumstances. These cuts divide the forward part of the spring plate into two, three, or more tongues which are separate and free from one another at their forward ends and are therefore adapted to bend independently of one another, but are rigidly connected together at their rear ends. The function of these tongues is to allow different parts of the support to yield independently of one another. That tongue or portion of the spring which underlies the inner side of the foot is wider than the other tongues, and is additionally stiffened by the turned up lip; this part or tongue is therefore less yielding than the others.

As a result of the construction thus described the outer and intermediate parts of the spring are adapted to yield in case the weight of the wearer is concentrated on these parts either as a result of standing on uneven ground or otherwise, whereby the outer part of the foot may descend far enough relatively to the portion of the plate which bears against the inner side of the arch, to exert the necessary and desirable pressure on that part of the foot. This is a feature of great advantage over the arch supports as heretofore made, since it causes the support to act uniformly on the inner part of the arch at all times.

What I claim and desire to secure by Letters Patent is:

1. An instep support having a relatively rigid portion to underlie the inner side of the instep and a relatively yieldable spring metal portion separate from the first portion to underlie the outer side of the instep.

2. An arch support comprising a body and a spring plate secured adjacent at its heel end to the body, the forward end of the spring plate being free of the body and being divided into a plurality of semi-independent spring tongues which extend longitudinally beneath the instep of the wearer.

3. An instep support comprising essentially a plate shaped to give support to a fallen instep, and having deep slots extending rearwardly from its forward end nearly to its heel end, which divide the part of the plate which underlies the instep of the wearer into a plurality of independently yieldable tongues.

4. An instep support having its forward end divided into semi-independent tongues, that portion or tongue which is adapted to

underlie the inner side of the instep being relatively stiff and that portion which underlies the outer part of the instep being relatively more flexible and yielding than the first named portion, being thereby adapted to yield when the bottom of the wearer's shoe is otherwise than perpendicular to the line of thrust of the wearer's foot, the inner

portion of the support being thus caused to maintain upward thrust of the desired intensity against the downward pressure of the wearer's foot.

In testimony whereof I have affixed my signature.

MICHELANGELO SANTELLA.
